UNITED STATES PATENT OFFICE

125,756

DESIGN FOR A COMBINED AUTOMOBILE LAMP AND SUPPORT THEREFOR

Harold J. Dobmeier, Kenmore, N. Y.

Application July 10, 1940, Serial No. 93,543

Term of patent 7 years

To all whom it may concern:

Be it known that I, Harold J. Dobmeier, a citizen of the United States, residing at Kenmore, in the county of Erie and State of New York, have invented a new, original, and ornamental Design for a Combined Automobile Lamp and Support Therefor, of which the following is a specification, reference being had to the accompanying drawings, forming part thereof.

In the accompanying drawings:

Fig. 1 is a side elevational view of a combined automobile lamp and support therefor embodying my design.

Fig. 2 is a front elevational view of the same.

Fig. 3 is a perspective view of the same.

Fig. 4 is a top plan view of the same with the lamp and the clamp members shown in the other illustrations omitted for convenience of illustration.

The dominant features of my design reside in the portions shown in full lines.

I claim:

The ornamental design for a combined automobile lamp and support therefor, substantially as shown and described.

HAROLD J. DOBMEIER.
